UNITED STATES PATENT OFFICE.

ALFRED FREDERICK BRONNER, OF MELBOURNE, AND ALFRED ARTHUR QUICK, OF NORTHCOTE, VICTORIA, AUSTRALIA.

GEARING.

1,144,807.

Specification of Letters Patent. Patented June 29, 1915.

Application filed August 16, 1911. Serial No. 644,834.

To all whom it may concern:

Be it known that we, ALFRED FREDERICK BRONNER, subject of the Emperor of Germany, and resident of 117 Collins street, 5 Melbourne, and ALFRED ARTHUR QUICK, subject of the King of Great Britain and Ireland, and resident of Barry street, Northcote, in the State of Victoria, Commonwealth of Australia, have invented Improvements 10 in Gearing, of which the following is a specification.

This invention relates to certain improvements in epicyclic speed reducing or speed multiplying gearing, embodying the use of 15 an oscillating wheel which engages with a fixed wheel and a rotating wheel, the motion being transmitted through the said rotating wheel.

The object of our invention is to provide 20 means whereby the forces about the central point of oscillation are symmetrically balanced, thus virtually supporting the central point of oscillation independently of the driving shaft, and operating cam thereon, 25 and relieving the high speed or driving shaft of the back thrust from the teeth. The effect of virtually supporting the central point of oscillation is to reduce the pressures on the journal bearings of the high speed or 30 driving shaft.

This invention consists of certain improvements in gearing which comprises an oscillating wheel operated with a cam without shoulders or abutments so that the said oscillating wheel and the cam have mutual freedom of lateral movement, the said oscillating wheel engaging with a fixed wheel and a rotating wheel, the motion being transmitted through the said rotating wheel.

40 Our improvements in gearings of this description comprise the duplication of the inner series of engaging teeth of the oscillating wheel by the provision of an additional wheel engaging therewith. In a gearing 45 constructed in accordance with this invention there are thus at least three series of teeth upon the oscillating wheel. The additional wheel referred to may be either a fixed wheel or a rotating wheel as the case 50 may be provided it insures the duplication of the inner series of teeth upon the oscillating wheel. The mutual pressure between the additional series of teeth afforded by the aforesaid duplication causes the forces acting 55 in the plane of rotation to be counter-

balanced about the central point of oscillation, and the high speed shaft is thereby relieved of the pressures due to such forces and is virtually supported.

In order that our invention may be better 60 understood we will now proceed to describe the same with reference to the accompanying drawing which is an elevation partly in section of a gearing (applied to a winding drum or winch) in which the balancing of 65 resultant pressure at the central point of oscillation is effected by the duplication of the inner engaging series of teeth on the oscillating wheel and the fixed wheel.

The fixed frame A is in the nature of a 70 pair of brackets or standards. The driving shaft B passes through from side to side, having means at either end for the attachment of driving pulleys or cranks as the case may be. Upon this driving shaft B is 75 mounted a cam D shown in section carrying the oscillating wheel E. The cam D is formed without flanges or side projections to allow of the wheel E having free lateral movement to automatically adjust itself to 80 its true working position upon the cam D. The wheel E is formed with duplicate series of teeth E' E' upon either side engaging fixed series of teeth F' upon fixed wheels F which are attached to the brackets or stand- 85 ards A. The oscillating wheel E has a duplicate series of teeth E² which gear with the series of teeth H' upon the inside of a drum or barrel M which thus acts as a winch and rotates upon the bosses of the fixed wheels F. 90 This drum or barrel M is adapted to form an oil box for the gearing. The before mentioned duplication of the series of teeth is arranged for the purpose of balancing the resultant pressure at the central point of 95 oscillation, thereby virtually supporting the said central point of oscillation.

In operation the driving shaft B is actuated by driving pulleys, cranks or other operative devices. The cam D upon this shaft 100 imparts an oscillating movement to the toothed wheel E. The two duplicate series of teeth E' are one more in number than the two duplicate series of fixed teeth F' so that for each complete rotation of the cam D the 105 said oscillating wheel moves forward in rotation to the extent of one tooth. The two duplicate series of teeth E² are one more in number than the two duplicate series of teeth H'. So that for every complete rota- 110

tion of the cam D the said oscillating wheel steps forward in rotation to the extent of one tooth. The resultant rotating movement imparted to the drum M is thus expressed by well known formula applicable for such reverted epicyclic gearing:—

$$1 - \left(\frac{F' \times E^2}{E' \times H'} \right)$$

- 10 In operation the load upon the drum M is transferred through the teeth H' to the teeth E² and from thence through the teeth E' to the teeth F' of the fixed wheels. Now these teeth F' resist the pressures of the teeth H' (through the medium of the oscillating wheel) in opposite directions and thereby relieve the high speed shaft B from any pressures due to the load. Assuming that the said teeth F' were not duplicated in 15 the manner shown it will be seen that the pressures from the teeth H' would be directly transmitted on to the high speed shaft.

20 In practice the oscillating wheel and the cam are so made that the center of gravity of the two combined coincides with the central point of oscillation, so that the balance

attained as above set out is not subjected to any disturbance due to the force of gravity.

30 We claim:

35 In epicyclic gearing, the combination of a fixed member, a rotatable driving member, a rotatable driven member, an oscillating wheel, a cylindrical cam arranged upon one of the said rotatable members at an oblique angle to its axis and having the oscillating wheel journaled thereon, the center of oscillation of said wheel being disposed inwardly with respect to the ends of the cam; inner 40 duplicate series of teeth provided upon both sides of the oscillating wheel and upon the fixed member at opposite sides of the said wheel to gear with each other, and an outer series of teeth provided upon the other rotatable member and the oscillating wheel at 45 one side of the latter to intermesh.

46 In testimony whereof we affix our signatures in presence of two witnesses.

ALFRED FREDERICK BRONNER.
ALFRED AERTH QUICK.
